UNITED STATES PATENT OFFICE.

HILAIRE DE CHARDONNET, OF PARIS, FRANCE.

APPARATUS FOR TREATING ARTIFICIAL-SILK AND LIKE THREADS.

1,243,489.

Specification of Letters Patent. Patented Oct. 16, 1917.

Application filed July 16, 1915. Serial No. 40,272.

To all whom it may concern:

Be it known that I, the Count HILAIRE DE CHARDONNET, a citizen of France, residing at 22 Place Malesherbes, Paris, in the Republic of France, have invented new and useful Improvements in Apparatus for Treating Artificial-Silk and like Threads, of which the following is a specification.

This invention relates to improvements in apparatus for treating threads of collodion or like filaments with reagents or other suitable liquids, in order to denitrate, bleach, dye, or similarly treat such threads under the best conditions of uniformity and regularity. The reagents which act upon the threads circulate through the mass of the latter under the action of centrifugal force, the threads to be treated being suspended axially and swiftly rotated in compartments containing the liquid. The threads are carried on bobbins provided with rings of radiating points along two or more circumferential lines. These bobbins are very light and afford a large hollow space inside, the threads while under treatment by the reagents being supported only by the radiating points, so that the liquid, reagent, denitrating or bleaching, or washing, or dyeing, is allowed to easily circulate through the matter.

The following description, which, with reference to the accompanying drawings, will enable the invention to be clearly understood and explain the means employed of supporting the threads on bobbins allowing a free circulation of the liquid reagent through the filaments, when suspended axially in compartments on central rotary spindles or shafts.

40. Figure 1 is a longitudinal section of a bobbin the component parts of which are adjusted ready for winding on thread from the twisting machine.

45. Fig. 2 is a longitudinal section of part of an apparatus with compartments for treating the bobbin with the usual reagents or liquids.

Fig. 3 is a plan of Fig. 2 omitting on one side the drive for the vertical spindles.

50. Fig. 4 is a transverse section along the line N N of Figs. 2 and 3.

Fig. 5 is a vertical section of a slightly modified form of apparatus particularly for dyeing and like operations, and

55. Fig. 6 is a plan of one of the circulating propellers employed in Fig. 5.

In order to put in practice this invention the bobbins usually employed in twisting machines are replaced by bobbins of small diameter provided with two or more rings of radiating points, from which the mass of twisted thread is suspended freely in order to undergo the subsequent liquid treatments in an open condition.

Referring first to Fig. 1, the improved bobbin is composed of a core or body A bored with a central hole *a* and provided in the example illustrated with two sets of radial rods terminating in points *b* *b'*, of which one set *b* are curved and the other *b'* are straight, the points serving to hold the mass of twisted thread wrapped on the bobbin when subjected to liquid treatment.

The best way to circulate the liquid reagent through all the threads is by the use of centrifugal power. For this purpose the bobbins, suitably isolated, might be mounted on supports within a centrifugal machine with liquid circulation, such as used for washing certain chemicals, for nitrating cotton, etc., but it is preferred to make the bobbins rotate on themselves within the reagents in the special apparatus forming part of this invention.

The conditions which this apparatus must fulfil are the following:

1. For each bobbin the amount of liquid reagent should correspond as nearly as possible with the amount of artificial silk wound on that bobbin.

2. The points from which the wound on threads are suspended must not, in any case, touch the sides of the tank or the adjoining bobbins.

3. Filling or emptying the tanks where the reaction takes place, must be effected quickly.

4. The temperature must be maintained at the degree required during the whole operation, and the bath must not undergo any substantial change.

An apparatus fulfilling all these requirements consists of a long watertight tank G divided along both its longer sides into vertical compartments H, either circular or polygonal in cross section, so that the space occupied by a bobbin within each compartment should correspond to the quantity of liquid reagent necessary and sufficient to treat the thread carried on that bobbin.

Above each compartment a vertical pulley I is placed and is given a swift rotary mo-

tion; transmitted to a spindle J suspended from the pulley I by a collar or equivalent connection. This spindle J which hangs freely without guides, carries a certain number of bobbins fitted with the artificial silk thread to be treated.

Disk plates *i* are screwed to the ends of the spindle J in order to wedge the bobbins tightly together and another like plate *i'* 10 may be placed at mid-length as shown. The plates *i* *i'* are of a diameter slightly exceeding that of the points *b* *b'* so as to avoid any contact of the latter with the compartment walls. Moreover the spindle J together with 15 the bobbins on it is self centering being freely suspended without guides.

In Fig. 4 it is assumed that one of the compartments H is filled with bobbins on a spindle J rotated by the means indicated or 20 other suitable driving gear, and that on the other side the driving gear has been stopped in order to replace treated bobbins (just de-nitrated for example) by others carrying fresh thread to be treated.

25 The middle part G of the tank is filled with water maintained normally at the temperature desired by means of steam or any heating or cooling means if required.

The vertical pulleys I on the rotary spindles J, with their bobbins, are set in motion 30 through belts or ropes *j* by means of a driving drum K, placed over the top of the machine extending over its whole length and driven by a pulley M or other convenient 35 means.

Each pulley I is carried in a movable frame N pivoted or hinged at *k*. It is thus possible to swing back each frame N as 40 shown on the right hand side of Fig. 4 in order to reach a compartment and remove one set of bobbins and replace it by another. In such case, the pulley I occupies a lower 45 position but remains vertical, its axle being in line with its spindle J as shown on the left hand side of Fig. 4. The vertical spindle J, laden with bobbins, is attached to the lower end of the pulley's axle by a pin or any other suitable means. A hook or catch *m* serves to fasten and hold fast the 50 movable frame N. When this frame is duly in its place the belt or rope *j* is stretched to maintain the rotation of pulley I and its connected spindle J and bobbins and a fresh 55 operation with a fresh set of bobbins may be started at once.

The divisions *n* separating the compartments H do not reach to the bottom of the tank, as may be seen in Fig. 5; they leave a free space C below which is slightly sloped 60 to insure the outflow of the liquid reagent used in the tank; and which is allowed to flow into the top of the compartments H.

An outlet tap *p* placed at the lowest part 65 controls the emptying of the tank; and each compartment may be fitted with a lid in or-

der to protect the workmen from the fumes emitted by the reagents.

The treatment of bobbins inside the apparatus takes place in the following manner:— 70 The series of bobbins strung on the spindles J are wedged between the plates *i* screwed on the ends of the rods, and lowered into the tank compartments H; the spindles J are then connected to the axles of the pulleys I and allowed to hang freely 75 from them; the liquid reagent is next admitted to the compartments, such reagents for instance as those used to denitrate the collodion threads, to bleach them, or eventually dye them. All the spindles J with 80 their bobbins are rotated simultaneously by starting the top horizontal shaft K. When the operation is completed the reagent is run off by means of the tap *p*, and water is admitted into the tank to wash the thread, 85 while the rotation of the bobbins is continued. Next the water is run off and rotation is maintained in order to dry partially, through centrifugal force the treated threads 90 on the bobbins.

When this partial drying is finished, the motion of the shaft K is stopped, the damp bobbins are taken off and left to dry in warm air, when they are taken to the winding machine.

95 During this operation the bobbins have retained both sets of points *b* *b'* but when they are taken from the machine still damp but with the water driven out by centrifugal force, the straight points *b'* are removed 100 and only the curved points *b* retained. The bobbins are then placed in the winding machine covered with a cap (not shown) the edge of which just reaches the level of the ring of curved points *b*.

105 The bobbins are then unwound by drawing off the thread from above, nearly following the line of the bottom axle. In this way the thread leaving the bobbin never catches in the curved points *b* which are 110 bent in a backward circumferential direction. The curved points *b* during the unwinding have no other function except that of supporting the whole mass of threads on the bobbin.

115 The apparatus can be employed to dye threads on bobbins as described or it can be arranged so as to dye in small lots, by operating independently in each compartment H. In this case all the compartments 120 H are isolated from each other and do not communicate at the bottom and each has its own outlet tap *p*.

Under these conditions, in order to preserve the homogeneity of the bath all 125 over and along the whole height of each compartment, the liquid circulating in the bobbin is moved not only through centrifugal force as previously described, but there is also a vertical circulation. For this 130

purpose there is fitted in each compartment (see Fig. 5) a pipe O passing through the warm water in the tank G and opening into the top and bottom of the compartment.

5 In order now that the disks *i* *i'* which are mounted on each spindle J will not form an obstacle for the free circulation of the liquid in the interior of the compartment, but will promote the circulation of the 10 liquid, the plain disks are replaced by small disks *r* with blades to act as propellers. These propellers *r*, one of which is shown in Fig. 6, are fixed on the vertical spindles J of the bobbins, and, rotating with it, displace the liquid vertically in each compartment H.

15 If the apparatus is employed for dyeing purposes in several of the compartments, they may be placed in communication by 20 means of side tubes and the dye liquor circulated throughout them.

What I claim as my invention and desire to secure by Letters Patent in the United States is:—

25 1. The improved apparatus for treating with liquids, artificial silk and like threads, comprising a tank divided into a middle longitudinal compartment and two series of side compartments, the middle compartment adapted to contain water maintained at the required temperature by suitable means, and the side compartments adapted to contain the liquid reagent, series of bobbins adapted to have threads to be treated wound thereon, 30 a rotary spindle suspended vertically and hanging freely upon which said bobbins are disposed, and means for rotating said spindle in such manner that the rotation of the self-centering spindles insures an active 35 circulation of the liquid reagent throughout the threads upon the bobbins substantially as herein set forth.

2. In apparatus for treating artificial silk and the like with reagents, the combination 45 comprising a tank divided into a middle longitudinal compartment and series of side compartments, the middle compartment adapted to contain water maintained at the required temperature by suitable means, and the side compartments adapted to contain 50 the liquid reagents, series of bobbins adapted to have threads to be treated wound thereon, a rotary spindle suspended vertically and hanging freely upon which said bobbins are disposed, means for rotating said

spindle, and a frame carrying said means for causing rotation arranged to shift said means to inoperative position.

3. In apparatus for treating artificial silk and the like with reagents, the combination 60 comprising a tank divided into a middle longitudinal compartment and series of side compartments, the middle compartment adapted to contain water maintained at the required temperature by suitable means, and 65 the side compartments adapted to contain the liquid reagents, said side compartments having partitions extending downward but not reaching the bottom, and the bottom sloping longitudinally of said compartments, means for draining said compartments, series of bobbins adapted to have 70 threads to be treated wound thereon, a rotary spindle suspended vertically and hanging freely in said side compartments upon 75 which said bobbins are disposed, and means for rotating said spindle.

4. In apparatus for treating artificial silk and the like with reagents, the combination 80 comprising a tank divided into a middle longitudinal compartment and series of side compartments, the middle compartment adapted to contain water maintained at the required temperature by suitable means, and the side compartments adapted to contain 85 the liquid reagents, series of bobbins adapted to have threads to be treated wound thereon, a rotary spindle suspended vertically and hanging freely upon which said bobbins are disposed, means for rotating said spindle, 90 and a hinged frame carrying said means for causing rotation whereby said means may be moved to inoperative position.

5. In apparatus for treating artificial silk and the like with reagents, the combination 95 comprising a container for the reagents, bobbins adapted to have thread wound thereon, means for supporting the bobbins in the container, and means for rotating said bobbins, said supporting means being 100 hinged for movement to inoperative position to permit the removal of the bobbins.

In testimony whereof I have signed my name to this specification in the presence of two subscribing witnesses.

HILAIRE DE CHARDONNET.
